UNITED STATES PATENT OFFICE.

ANTON FLETTNER, OF BERLIN-SCHONEBERG, GERMANY.

STEERING GEAR.

Application filed January 25, 1923. Serial No. 614,915.

To all whom it may concern:

Be it known that I, ANTON FLETTNER, a citizen of Germany, residing at Berlin-Schoneberg, Germany, have invented certain new and useful Improvements in Steering Gears, of which the following is a specification.

My invention relates to steering gears for water and air craft and in particular 10 to steering gears of the kind in which one or several auxiliary rudders are provided with the aid of which the main rudder is controlled. With rudder arrangements of this kind the gear for actuating the auxiliary rudder or rudders and for effecting the 15 relative movements between this or these rudders, and the main rudder respectively must be capable of answering certain conditions, such as I have explained in my 20 former applications for patent of the United States Ser. Nos. 392,839 and 392,840.

As stated in the specifications forming 25 part of these applications, the steering gear must be so designed that when the main rudder has been deflected by the auxiliary rudder, this latter is moved back into its zero-position, but that also in the case of undesired movements of the main rudder the auxiliary rudder is so adjusted that it moves 30 the main rudder back into its zero-position.

In the former application above referred to I have proposed to house the gear members in a gear box located in the hull directly above the main rudder shaft and carried by 35 that gear member which transmits the motion from the gear box to the rudders through the hollow rudder shaft or journal. This gear box will, as a rule, move together with the rudder, whereas a second gear box or base plate is provided which supports 40 the gear members, the position of which relatively to the hull is not altered. Owing to this arrangement the whole operating gear is easily accessible from the hull so that 45 it can be permanently attached and is not influenced by disturbances caused by water or air currents or by foreign bodies.

The present invention has for its object 50 certain arrangements of the steering gear above referred to which are designed to restrict as far as possible the number of gear members provided for moving the rudder to simplify the shape of such members in order to obtain the maximum security

of service and to render all driving members 55 easily accessible in the hull.

Thus a single transmission member is made to extend along the rudder shaft or through it, if said shaft is hollow, this member transmitting the rotary motion to 60 the auxiliary rudder, and in the rudder itself, or in caps attached thereto a transmission gear of the simplest kind, such as a parallel crank gearing, is provided.

This gearing is preferably constructed 65 to form a double parallel-guide. It is preferably disposed, as far as feasible, in the upper part of the rudder; it may, however, be divided in two parts in such a manner, that part which is located nearest to the 70 auxiliary rudder, is housed in the upper part of the main rudder, whereas the other part is located in the proximity of the rudder axis, or the rudder journal and near the lower edge thereof. This arrangement 75 renders it possible to provide a rudder journal of comparatively great length and great simplicity affording full protection for the guide members of the parallel crank gearing and being subjected only to moderate 80 stresses.

In the drawings affixed to this specification and forming part thereof a steering gear embodying my invention is illustrated diagrammatically by way of example. 85

In the drawings—

Figure 1 is a side elevation partly in vertical section and

Figure 2 is a corresponding plan, the main rudder journal being, however, omitted. 90

Referring to the drawings *a* is the main rudder capable of turning freely about its axis; *b* is the auxiliary rudder fixed on its spindles; *c* is the main rudder journal through which extends a spindle *d* transmitting motion to the auxiliary rudder *b*; *t* is the gear box and *p* is an electromotor fed with current through mains *q* and serving to operate suitable gearing enclosed in the gear box by means of bevel gearing *r*, 100 *v*. *w* is a quadrant insert between the gear box and the spindle *d* and serving for actuating the main rudder in an emergency. Spindle *d* has attached to its lower end a double-armed lever *e* connected with another 105 double-armed lever *f* by two parallel rods *g*, the members *e f g* forming the first half of the double parallel crank gearing near the

lower edge of the main rudder *a*. They are connected with the second half of this gearing near the journal *c* by a second vertical spindle *h* carrying at its lower end the 5 double-armed lever *f* and at its upper end another lever *i*, which is connected by parallel rods *l* with a fourth double-armed lever *k* fixed to the upper end of the spindle *m* of the auxiliary rudder *b*. The members *i l k* 10 form the second half of the double parallel crank gearing, the two halves being connected with each other by the shaft *h*.

The use of a double parallel crank gearing and the arrangement of the two valves at 15 different levels are not restricted to steering gears the other members of which are located in the hull, but may be used as well in those cases where certain members of the gearing are disposed on or in the main rudder body. By sub-dividing the double parallel crank gearing in two halves, it is possible in either case to protect the greater part thereof from exterior influences, for instance, if the rudder is dragged along upon the 20 ground, this part being accessible from above in every case. It may further be specially protected from above by a cover plate *o* or the like.

I wish it to be understood that I do not 30 desire to be limited to the exact details of construction shown and described, for obvious modifications will occur to a person skilled in the art.

I claim:—

1. Steering gear for water and air craft comprising in combination a ship's hull a main rudder shaft projecting from said hull and a main rudder freely movable about its axis, an auxiliary rudder spindle carried by 35 said main rudder and an auxiliary rudder on said spindle, a driving spindle extending axially along said shaft all the means for operating said driving spindle being disposed inside said hull and only a parallel 40 crank gearing being disposed outside said hull and connecting said driving spindle with said auxiliary rudder spindle.

2. Steering gear for water and air craft comprising in combination a ship's hull, a

hollow main rudder shaft projecting from 50 said hull and a main rudder freely movable about its axis, an auxiliary rudder spindle carried by said main rudder and an auxiliary rudder on said spindle, a driving spindle extending axially through said shaft all the 55 means for operating said driving spindle being disposed inside said hull and only a parallel crank gearing being disposed outside said hull and connecting said driving spindle with said auxiliary rudder spindle. 60

3. Steering gear for water and air craft comprising in combination a main rudder shaft and a main rudder freely movable about its axis, an auxiliary rudder spindle carried by said main rudder and an auxiliary 65 rudder on said spindle, a driving spindle extending axially along said shaft and a parallel crank gearing connecting said driving spindle with said auxiliary rudder spindle, said gearing being subdivided in two halves, 70 one being disposed near the upper and one near the lower edge of said main rudder.

4. Steering gear for water and air craft comprising in combination a main rudder shaft and a main rudder freely movable 75 about its axis, an auxiliary rudder spindle carried by said main rudder and an auxiliary rudder on said spindle, a driving spindle extending axially along said shaft and a parallel crank gearing extending through said 80 main rudder and connecting said driving spindle with said auxiliary rudder spindle.

5. Steering gear for water and air craft comprising in combination, a main rudder shaft and a main rudder freely movable 85 about its axis, an auxiliary rudder spindle carried by said main rudder and an auxiliary rudder on said spindle, a driving spindle extending axially along said shaft and a parallel crank gearing extending through said 90 main rudder and connecting said driving spindle with said auxiliary rudder spindle, said gearing being subdivided in two halves, one being disposed near the upper and one near the lower edge of said main rudder. 95

In testimony whereof I affix my signature.

ANTON FLETTNER.
